2 SHEETS-SHEET 2

UNITED STATES PATENT OFFICE.

EDWARD ERONEN, OF FITCHEBURG, MASSACHUSETTS.

SLED.

Application filed January 31, 1921. Serial No. 441,158.

To all whom it may concern:

Be it known that I, EDWARD ERONEN, a citizen of the Republic of Finland, residing in Fitchburg, county of Worcester, and 5 State of Massachusetts, have invented certain new and useful Improvements in Sleds, of which the following is a full, clear, and concise description.

My invention relates to sleds, and may be 10 used with sleds of many different kinds, but is peculiarly adapted for use upon motor sleds, such, for instance as sleds which are propelled by means of rotating propellers of the type generally used upon aeroplanes.

15 More particularly stated, I seek to produce a sled, preferably driven by an aeroplane propeller, and of a type suitable for travel upon both ice and snow, and provided with improved runners and with 20 steering gear connected with said runners for actuating the same.

My invention further contemplates improved brake mechanism, arranged to cooperate with my improved runners, for the 25 purpose of quickly overcoming the momentum of the sled, so as to bring the sled to a stand still without shock and without danger, within a very short distance of travel.

30 My invention further contemplates various improvements in the construction of the sled, for the purpose of improving the general efficiency of the device.

Reference is made to the accompanying 35 drawings forming a part of this specification, and in which like reference characters indicate like parts throughout the several figures.

Figure 1 is a plan view of my improved 40 sled.

Figure 2 is a side elevation of the same.

Figure 3 is a fragmentary front elevation of the device.

Figure 4 is a fragmentary section indicating the manner in which each of the keel 45 runners is mounted.

A pair of ski runners are shown at 5, 6, and have the form of wide boards having slightly curved cross sections and provided 50 with upturned front ends. These runners are provided with metallic face members 7, 8 made of sheet metal and serving the purpose of tires.

Connected with the runners 5 are a pair 55 of frame beams 9, 10, and engaging the rear ends of these frame beams is a cross board

11, resting upon angle irons 12 and serving as a seat for the operator.

Parallel with the board 11, and resting upon the frame beams 9, 10 are two cross 60 boards 13, 14. Resting upon these cross boards are a pair of relatively short boards 15, 16, serving as braces and each extending in the direction of the length of the sled. At the front end of the sled a cross beam 17 65 is secured to the frame beams 9, 10 and to the ski runners 5, 6.

Mounted rigidly upon the frame beams 9, 10 are a pair of frame members 18, 19, each having the general form of an inverted V. 70 These frames are braced by metallic rods 20, 21 extending between them.

Connected with the runners 16 and extending upwardly therefrom are tubular columns 22, and extending through these tubular columns are rods 23, provided with heads 24 and having the form shown more particularly in Figure 4. The rods 23 are fitted with nuts 25, whereby they are drawn tight. There are two pairs of these rods, 80 exactly alike, one on each side of the sled. The two rods 23 shown in Figure 4 extend through an angle iron 26, the latter being provided with a portion 27 extending downwardly and secured by bolts 28 to a runner 85 30. Another runner 29 is provided quite similar to the runner 30. These two runners 29, 30 are of the type known as keel runners, and are substantially parallel with each other. 90

The keel runners 29, 30 are made preferably of spring steel or brass, and are thickest where they are connected with the downwardly extending portions 27 of the angle iron 26. From this point they taper in 95 thickness, both toward the front and rear of the sled. They may be five-sixteenths of an inch thick where they are connected with the number 27, tapering off to about five-sixteenths of an inch in thickness at their front 100 and rear ends.

Mounted upon the cross board 13 is a motor 31, which may be either an internal combustion engine or any other kind of motor sufficiently light for the purpose and capable of developing a very high speed. Connected with the motor 31 by means of a clutch pulley 33 is a shaft 32. A clutch 34 is used for the purpose of throwing the shaft 32 into and out of action as driven by the 110 motor 31. A foot lever 35 is connected with the clutch 34, and so positioned that it may

be operated and controlled by the operator as he sits upon the seat 11. Engaging the pulley 22 is a belt 36, which also engages a pulley 37. This pulley 37 is mounted firmly 5 upon the end of a shaft 38, the latter extending horizontally through, and being supported by, a pair of bearings 39, 40. A propeller 41 is mounted upon the shaft 38, so as to turn therewith when this shaft is 10 driven from the motor 31.

A steering wheel appears at 42, and is mounted rigidly upon a revoluble steering rod 43, the latter extending through a tubular steering post 44. Mounted rigidly upon 15 the front or lower ends of the steering rod 43 is a crank 45. A pitman 46 is connected with the crank 45, and is also connected with an actuating bar 47. The actuating bar 47 extends nearly the full width of the sled, 20 and at its ends is pivotally connected with the two keel runners 29, 30.

The operator by turning the steering wheel 42 to a limited extent in either of two directions, can cause the pitman 46 to pull 25 or push the actuating bar 47 in the direction of its length, thus bending or swaying the front end portions of the keel runners 29, 30.

The keel runners 29, 30 are more or less 30 flexible throughout their entire lengths. Each of these keel runners, because of its form above described—that is, it being thick 35 in the middle and relatively thin toward its ends—is adapted to bend throughout its entire length. Not only that but its curvature in flexing has a tendency to distribute itself automatically throughout the length of the runner. This is especially true because the 40 rear end portion of each runner has a tendency to trail through the path made by the front end, as the runner cleaves its way through snow or across ice. The result is that the keel runners develop a minimum of friction from their engagement with either 45 ice or snow, or a mixture of ice and snow. These runners exert little or no side drag upon either ice or snow. By their action 50 they reduce to a minimum the amount of cleavage and scraping action which can develop as between them and the medium over which or through which they are adapted to travel.

It will be noted that aside from the steering gear and connections therefrom to the 55 keel runners, the keel runners are not by any means rigidly held in position relatively to the frame work of the sled. This is true because each keel runner is disconnected entirely from the ski runner with which it is 60 associated, except where the keel runner is secured by the bolts 28. Thus each keel runner has very little restraint upon its flexibility. It is for a very short distance, approximating its middle portion, secured 65 rigidly, but at all other points is free to

bend. Its flexibility is therefore very great, and moreover is distributed to great advantage for the purpose of enabling the keel runners to bend uniformly throughout their length. 70

In consequence of this arrangement, the sled is well adapted to make exceedingly short turns, and in making any sort of turns the power wasted is reduced to a minimum. Actual trial has demonstrated that my sled 75 can be driven and steered so as to execute circles almost perfect in rotundity and of surprisingly short diameter.

The ski runners 5, 6, with their upturned ends and metallic tires having considerable 80 spread of surface, have a tendency, when passing over snow, to pack the snow upon which they rest, thus increasing its density and its stiffness. In doing this, the ski runners prepare the snow for the action of the 85 keel runners. That is to say, the keel runners are enabled to cut clearly defined and sharply delineated paths through the snow thus prepared by the action of the ski runners. Another way of stating the same 90 thing is, that the ski runners, having weight upon them and gliding rapidly over the snow, have a tendency to press upon the snow just hard enough to enable the keel runners to obtain a good 95 grip in the snow. On the other hand, if the sled is passing over hard and solid ice and in the absence of snow, the keel runners alone engage the ice, and the ski runners can do no harm as they are supported out of 100 engagement with the surface of the ice.

A pair of brake blades are shown at 48, 49, and are mounted upon a shaft 50. This shaft is supported by bearings, one of which is shown at 51, in Figure 2. A brake lever 52 105 is mounted upon the shaft 50, and is used for actuating the brake blades. Each of these brake blades is twisted slightly or rendered spiral, so as to exert, when in action, a scooping effect upon any loose snow with which 110 it is forced into immediate engagement, by the rocking of the shaft 50. Each brake blade 48, 49 is so shaped and arranged that when the blade is swung downwardly by action of the brake lever 52, the brake blade 115 acts somewhat like a plow point, gathering loose snow and dragging it forward, so as to wedge the snow laterally against the adjacent keel runner. Thus each brake blade coacts with the keel runner immediately adjacent for the purpose of continuously compressing snow, and continuously dragging portions of the snow thus compressed. This action increases the effectiveness of the 120 brake blades. Each brake blade acts in 125 two distinct ways. If forced downwardly quite hard it scrapes or drags through the snow and upon the ice; and if any soft snow or mass of small pieces of broken ice lie within its path, this snow or 130

ice is continuously compressed by being forced laterally against the keel runner immediately adjacent. In practice, and especially when the sled is travelling over snow more or less soft, each brake blade leaves behind it a trail of snow more or less compressed, and formed into a substantially continuous row, comparatively narrow and in close proximity to the track made by the 10 keel runner.

In consequence of the double braking action brought about by each brake blade as above described, the sled can be brought quickly to a stand still from a high rate of 15 speed, and this too, without shock. Thus the brake can be made to serve every purpose of an emergency brake. Again, the operator by the application of a slight pressure upon the brake lever can bring about a 20 comparatively gentle braking action, such as will not ordinarily have any effect upon the direction in which the sled is traveling, and will simply cause a reasonable reduction in speed, depending upon the pressure 25 applied to the brake lever.

The operation of my device may be readily understood by the foregoing description.

The parts being assembled and arranged as shown and described, the operator sits 30 upon the seat 11, and readily controls the motor, the steering wheel and the brake lever, in the manner above set forth.

I do not limit myself to the particular mechanism shown, as variations may be 35 made therein without departing from my invention, the scope of which is commensurate with my claims.

Having thus described my invention, what I claim as new and desire to secure 40 by Letters Patent is as follows:

1. A device of the character described, comprising a sled body provided with a

ski runner, a keel runner disposed below said ski runner and so formed as to be flexible, said keel runner being secured by its 45 middle portion to said ski runner and disconnected from said ski runner along the front and rear portions of the keel runner, and means controllable at the will of the operator for flexing the front portions of said 50 keel runner.

2. A device of the character described, comprising a sled body, a ski runner mounted thereupon, and a keel runner connected with said body and being flexible, said keel 55 runner being provided with a thick middle portion and with thinner end portions, for the purpose of affecting the flexibility of the keel runner.

3. In a device of the character described 60 the combination of a sled body ski runners mounted thereupon, keel runners carried by said sled body and each provided with a rigid portion and with a flexible portion extending forwardly of said rigid portion, 65 and steering mechanism connected with the forwardly extending portion of said keel runner for the purpose of bending the same.

4. A device of the character described, comprising a sled body, an angle iron connected thereby and extending downwardly 70 therefrom, and a keel runner having a middle portion secured to said downwardly extending portion of said angle iron, said keel runner being provided with flexible portions 75 extending in opposite directions from said middle portion, the portion of said keel runner extending in one direction being free so as to enable it to readily flex, and the portion of said keel runner extending in the direction opposite the last mentioned direction being movable at the will of the operator. 80

EDWARD ERONEN.
